UNITED STATES PATENT OFFICE.

KRAFT BOOTH, OF PHILADELPHIA, PENNSYLVANIA, ASSIGNOR TO
GILLINDER & SONS, INC., OF PHILADELPHIA, PENNSYLVANIA.

DESIGN FOR AN ARTIFICIAL-LIGHT REFLECTOR.

No. 38,725.

Specification for Design.

Patented Aug. 6, 1907.

Application filed July 10, 1907. Serial No. 383,138. Term of patent 14 years.

To all whom it may concern:

Be it known that I, KRAFT BOOTH, a citizen of the United States, and a resident of the city of Philadelphia, in the county of Philadelphia and State of Pennsylvania, have invented a new, original, and ornamental Design for an Artificial-Light Reflector, of which the following is a specification, reference being had to the accompanying drawing, in which—

Figure 1 is a view representing the exterior surface of an artificial light reflector showing my design. Fig. 2 is a view representing the reverse or interior surface of said reflector.

The reflector is of transparent glass, the interior surface being smooth and the exterior surface partly ground or frosted and partly covered with ornamental radial prisms.

The radial prisms extend from the outer edge of the reflector toward the neck or collar thereof, while the ground or frosted surface is between said neck or collar and said prisms.

The ornamental radial prisms as they appear from the outside of the reflector are indicated in Fig. 1 by full lines. They are also visible on the interior of the reflector, their appearance from this aspect being indicated by dotted lines in Fig. 2.

I claim as my invention:—

The ornamental design for an artificial light reflector, as shown and described.

KRAFT BOOTH.
